FUEL SUPPLY UNIT FOR OIL BURNERS
OR THE LIKE

Arthur C. Kleckner and Harrison E. Fellows,
Racine, Wis., assignors to Webster Electric
Company, Racine, Wis., a corporation of Wis-
consin

Application March 14, 1934, Serial No. 715,441

10 Claims. (Cl. 103—42)

The present invention relates to fuel supply units for oil burners or the like, and the present fuel supply unit comprises improvements over that disclosed in the prior application of one of the applicants herein, Arthur C. Kleckner, Ser. No. 604,834, filed April 12, 1932, for Multi-stage pumps and pumping systems.

Among the advantages and objects of a fuel supply unit of the type covered by these applications are the following:

(1) The elimination of difficulties caused by fluid tight packings, by a substantial reduction in the fluid pressure to which the packing is subjected.

(2) Supply of liquid fuel to an oil burner at substantially constant pressure and volume in spite of the variations in suction resistance and/or nozzle resistance which might be caused by obstructions in either the nozzle or the suction pipes or by variation in head of the liquid in the supply tank.

(3) Provision of a fuel supply unit which is self-priming, dependable, capable of immediately performing its functions on starting at any time, even though the tank and pipe lines have been completely emptied since the last operation of the fuel line.

Another object of the invention is the provision of an improved fuel supply unit of the type described which eliminates the difficulties sometimes encountered in the form of pump noise. The pump being of a gear type, the action of the gears causes periodic pulsations in the flow of the fuel oil, and these pulsations have a tendency to be carried back through the pipe to the tank. The tank acts under these conditions like a sounding board, producing, under some conditions, a sound which is distinctly audible and which would be a marked disadvantage in the case of an oil supply unit or pump which is intended to be used upon oil burners for homes, where noiseless operation is not only desirable but very essential if the unit is to meet with wide acceptance under all conditions.

Another object of the invention is the provision of an improved fuel supply unit for oil burners or the like which is adaptable to a one pipe or a two pipe system without any external connections for this purpose, but also having no valves or other devices with which the ordinary householder could tamper.

Another object of the invention is the provision of an improved fuel supply unit for oil burners or the like which is adapted to eliminate the multiplicity of connecting pipes heretofore

found necessary in connecting various parts, such as pumps, strainers, regulating valves, etc., and the provision of a single unit device which is capable not only of providing fuel under proper pressure and volume, but also capable of straining out any foreign matter which might clog the nozzle, and of regulating the pressure of the liquid fuel at the nozzle in such manner as to provide as far as possible a substantially constant supply of fuel at substantially constant pressure, in spite of the various factors which might tend to diminish or increase the volume or pressure.

Other objects, features and advantages of the invention will be apparent from the following description and from the accompanying drawings, in which similar figures represent similar parts throughout the several views.

Referring to the drawings, of which there are three sheets:

Fig. 1 is a diagrammatic illustration of a fuel supply system, including the present fuel supply unit;

Fig. 2 is a vertical sectional view taken through the fuel supply unit of Fig. 1 on the plane of the line 2—2 in Fig. 4, looking in the direction of the arrows;

Fig. 3 is a sectional view taken through the fuel supply unit on the plane of the line 3—3 of Fig. 2, looking in the direction of the arrows;

Fig. 4 is a cross sectional view through the fuel supply unit, taken on the plane of the line 4—4 of Fig. 2, which is a horizontal plane with respect to Fig. 1;

Fig. 5 is a sectional view taken on the plane of the line 5—5 of Fig. 2, showing the shape of various parts and the connection of various conduits of the fuel supply unit;

Fig. 6 is a fragmentary sectional view taken on the plane of the line 6—6 of Fig. 4, showing the shape of various parts of the pump and the connections of various conduits;

Fig. 7 is a vertical sectional view taken on the plane of the line 7—7 of Fig. 6, looking in the direction of the arrows, passing through the axes of the pump shafts, with the pump gears in elevation;

Fig. 8 is a transverse sectional view taken on the plane of the line passing through the axis of the drive shaft, showing the preferred type of oil seal;

Fig. 9 is a fragmentary vertical sectional view similar to that of Fig. 2, showing the preferred form of strainer and a silencer for preventing the singing noise that might otherwise go back to the tank in some installations.

55

Referring to Fig. 1, 10 indicates in its entirety the present fuel supply unit, which is preferably driven by an electric motor 11, which may be the same motor that drives the fan or other mechanism connected with the oil burner in question. The complete fuel supply installation includes a tank 12, shown diagrammatically with a supply of fuel oil 13, and the suction pipe 14 leading to the fuel supply unit 10 is immersed in the liquid fuel 13. The return pipe 15, which is connected to the return port of the fuel supply unit 10, communicates with the tank 12. Another pipe 16 conveys liquid fuel from the fuel supply unit 10 to an oil burner nozzle or other device for consumption of the liquid fuel.

While the present fuel supply unit is particularly adapted to be used for oil burners, it should be understood that the device is also of general application and may be utilized wherever it is desirable to provide a supply of liquid at substantially constant pressure and volume with or without the strainer for cleaning the liquid out or the pressure regulator for maintaining close regulation of the pressure.

23 The oil supply unit 10 preferably comprises a housing 17 which may be made of cast metal, and which is preferably provided with a pair of laterally extending attaching flanges 18, 19 provided with bores 20 for receiving attaching bolts. The attaching flanges 18, 19 are carried by the rear wall 21 of the central part of the housing, which also carries a substantially cylindrical wall 22 surrounding the pump shaft 23. The wall 21 is provided with a cylindrical bore 24 forming a bearing for the pump shaft 23, and the cylindrical wall 22 surrounds the counterbore 25 for housing a spring and seal.

Referring to Fig. 8, this is a similar fragmentary view of an improved and preferred form of oil seal, which is preferably used in the devices embodying the invention. In this case, the plate 21 is formed with an annular wall 22 for housing the oil seal, and with an inwardly extending sleeve 180, which is reduced in size at 181 for providing an annular seat 182 for the spring 183.

50 The drive shaft 23 is located in the cylindrical bore 24 and projects from the cover plate 184 through an enlarged aperture 185. The cover plate 184 is substantially frusto-conical in form and provided with a radially outwardly extending attaching flange 186, having apertures for receiving the screw bolts 187. The attaching flange 186 also has a cylindrical flange 188 which embraces the reduced cylindrical end 189 of the annular wall 22 and is also adapted to receive a pair of gaskets 190, 191 which are located on the opposite sides of the diaphragm 192.

60 The diaphragm 192 is apertured, as are the gaskets 190, 191, to receive screw bolts 187, and by means of the attaching flange 186, gaskets, and screw bolts, threaded into the bores in the annular wall 22, the diaphragm 192 has a fluid-tight connection with the end of the annular wall 22.

65 The diaphragm 192 supports a metal sleeve 193 having a flat end surface 194 and having radially outwardly extending flange 195. The diaphragm is provided with a suitable aperture for receiving sleeve 193, and sleeve 193 is clamped on the diaphragm by means of a metal ring 196. The sleeve 193 may be spun over to secure the ring 196 in place, or the sleeve 193 may be soldered or otherwise permanently secured to the diaphragm 192. A coil spring 183, mounted on the reduced 70 end 181 of sleeve 180, engages the diaphragm 192

and urges the sleeve 193 toward the right, in Fig. 8.

The sleeve member 193 engages a hardened threaded sleeve member 197, which likewise has a flat surface 198 on its end, and sleeve member 197 is mounted to rotate with the shaft 23. Sleeve member 197 is formed with a threaded outer surface 199 for receiving a complementary threaded sleeve 200, which has a frusto-conical inner surface 201. Sleeve member 197 has a frusto-conical inner surface 202, and these two frusto-conical surfaces compress and engage a soft metal annulus 203, forcing it into engagement with the shaft 23 and fixedly securing the sleeve member 197 to the shaft with a fluid-tight joint between 15 the sleeve member 197 and shaft 23.

The actual seal takes place at the engaging surfaces 194 and 198 which are resiliently kept in engagement with each other by the spring 183. The body of the end plate may be provided with 20 a bore 204 leading from the chamber 205 back through the low pressure suction side or low pressure output side. In case it is connected to the low pressure output side, the shaft is grooved at 206 to permit the oil, which is forced in to the chamber 205, to find its way back to the reservoir. Such an arrangement would be used where the fuel oil has lubricating properties. In case the fuel oil has foreign materials which might tend to affect the sliding seal at 194, 198 deleteriously, 30 then the bore 204 should be connected to the suction side of the low pressure stage to carry back to the pump such leakage as might take place along the shaft in the bore 24 to maintain the surfaces 194, 198 in a clean condition by means of the flow 35 of fuel oil.

A cover plate 26 is provided with a reduced cylindrical portion 27 fitting in the counterbore 25 and with a bore 28 for receiving a bearing sleeve 29 having a radially outwardly extending 40 flange 30. Cover plate 26 has a plurality of bores 30 and counterbores 31 for receiving the bodies and heads of the securing screw bolts 32, which are threaded into registering bores 33 formed in the wall 22. A suitable gasket 34 may 45 be interposed between the cover plate 26 and the plane gasket seat which is provided by the outer end of wall 22. Cover plate 26 is preferably substantially circular, conforming to the outer surface of the cylindrical wall 22. 50

Within the counterbore 25 pump shaft 23 is preferably surrounded by a helical spring 35 which is compressed between the washers 36, 37, each of which engages a fluid tight packing 38, 39 of leather, rubber, soft metal, or other suitable material. 55

It should be noted that the seal which is shown in Figs. 3 and 4 is of an alternate type as compared with that disclosed in Fig. 8, and while either of these seals may be employed, that disclosed in Fig. 8 is preferred. 60

Referring again to Fig. 2, the housing 17 may be conveniently described by referring to the three parts, namely, the regulator valve housing 40, the pump housing 41, and strainer housing 42, although the major portion of all three of these divisions is comprised in a single integral casting. 65

These housings contain chambers which may be designated as the valve chamber 112, the 70 pump chamber comprising counterbores 92-95 in the gear housing 58 and the strainer chamber 43.

The strainer housing portion 42 at the right, as shown in Figs. 2 and 4, comprises a substan- 75

tially cylindrical formation having its major axis extending vertically in Fig. 1 or at right angles to the pump shaft 23. This cylindrical strainer housing 42 is preferably formed with a substantially cylindrical strainer chamber 43, which is provided at the lower right hand of Fig. 2, with an inlet port 44 formed in a laterally extending lug 45, and provided with pipe threads for receiving the suction pipe 14. It is also preferably provided with a threaded clean-out opening 46 centrally located in the bottom of the strainer housing portion 42 and provided with pipe threads for receiving the closure plug 47.

The wall 42 of the strainer chamber is preferably provided at its top with a plane surface 48 forming a seat for a suitable gasket 49, which is compressed against the surface 48 by the cover plate 50. Cover plate 50 may comprise a substantially circular casting of the same size as the cylindrical strainer housing 42 and provided with a reduced cylindrical portion 51 adapted to fit within the cylindrical bore 52 of the strainer housing. A plurality of screw bolts 53 pass through the cover plate 50 and are threaded into the wall of the strainer housing 42 to secure the cover plate firmly in place. The cover plate 50 may also be provided with a centrally located threaded bore 54 with a threaded closure plug 55 having a non-circular end 56 for receiving a wrench. This closure plug is convenient for use in observing the inside of the strainer chamber 43 at the top and for connection of a gauge, if desired.

The strainer housing portion 42 is integrally joined to the pump housing 41, but separated therefrom, by the wall 57 which forms a part of the strainer housing. The pump housing 41, which forms an integral casting with the strainer housing 42 and regulator valve housing 40, may comprise a substantially oval portion of the casting which is provided with an inner gear housing 58 spaced from the outer wall 59 of the pump housing and forming an intermediate oil chamber 60. Various oil chambers and conduits in the oil supply unit are, of course, formed by coring out these portions of the casting, and the gear housing 58 must, of course, be suitably joined to the pump housing 41 by sections of metal 61 at the left and 62 at the right, where it is desired to locate conduits extending to the valve chamber and strainer chamber respectively.

The strainer housing portion 42 has its wall provided with an inwardly projecting annular shoulder 63 preferably having a flat upper surface for engaging a sheet metal partition 64. Sheet metal partition 64 is substantially circular in shape and may be in close frictional engagement with the wall of the bore 52 in the strainer housing 42, or it may fit loosely, being held by wire 66. Above the annular shoulder 63 and spaced sufficiently from the upper surface of annular shoulder 63 to permit insertion of the partition 64, is an outwardly extending annular groove 65 in the wall of the strainer housing 42. A resilient spring wire 66 of steel or other suitable material is coiled into circular form and sprung outwardly into the groove 65, the groove 65 being so located that the wire 66 locks the partition 64 in place. Partition 64 is provided with a centrally located bore 67 which is adapted to receive the end 68 of a perforated metal tube 69. Tube 69 is threaded into the bore 67 and secured in place by a threaded locking member 70, which is threaded home on the end of the perforated tube 69 against the partition 64.

The lower end of the tube 69 may be closed by any suitable means, such as an end plate, welded, soldered, or otherwise secured to close the end, but is preferably provided with a pair of axially extending lugs 71 which pass through the end plate 72 and are bent over to secure the end plate. The tube is in communication with the interior of the strainer chamber 43 through a plurality of apertures 73 located at random in the side of the tube 69, or apertures 73 may be suitably spaced to register with annular chamber 80.

Removably supported upon the perforated tube 69 are a plurality of strainer units 74. These strainer units may be removed and replaced when they become clogged or otherwise disabled, and they preferably comprise strainer units of the type shown in the prior application of Harrison E. Fellows, Serial No. 603,734, filed April 7, 1932, for Strainers and methods of making strainer units.

In some embodiments of the invention, the features of the strainer may correspond in all of their details to those described and shown in the above-mentioned Fellows application.

For example, each of the strainer units 74 is identical in construction with the upper one which is shown in section and which comprises upper and lower discs 75 of wire screen supported on a pair of metal collars 76 in spaced relation to each other. The collars 76 are annular stamped sheet metal members having a substantially cylindrical central portion 77 with an outwardly extending annular flange 78. The cylindrical portion 77 is provided with a plurality of spaced apertures 79 communicating with the interior annular chamber 80 and thence with the apertures 73 of tube 69.

The two collars 76 are identical and their flanges 78 engage each other, the collars extending in opposite directions. At the outer end of each collar there is provided an inwardly extending flange 81, which is bent outward upon itself at 82 to clamp the wire screen disc 75 to the collars 76, the wire screen disc having an aperture to receive the collar.

After the collars are so secured to the wire screen discs, they are provided with a circular wire loop 83 which is spaced slightly from the outer edge of the discs and which serves to hold the discs spaced from each other adjacent their outer edges. The outer edge portions 84 of the screen discs 75 are forced into engagement with each other, as shown, and secured by soldering said outer edge portions firmly to each other in position, shown in Fig. 2.

Referring to Fig. 9, this is a fragmentary view similar to Fig. 2, showing a modified form of strainer unit which is also provided with a silencer for preventing the singing noise which otherwise goes back to the tank from the pump.

In this embodiment the strainer housing 42 is of similar structure to that previously described, and the strainers are supported upon the partition 64 which rests on the annular flange 63. The wire 66 is mounted in the groove 65 for securing the partition in place, and is preferably provided with two upwardly turned ends 207, which may be grasped by means of a pair of pliers in contracting the wire out of the groove 65 to remove the wire.

The strainer units 74 are similar in structure to those previously described, each being formed of discs 208, 209 of foraminous material, such as

screen, which are clamped by the spacing collars 77 and forced to frusto-conical form.

The spacing wire 210, however, is located flush with the periphery of the screens 208, 209, and the 5 edge space between the screens and the outer surface of the wire 210 is filled with solder 211. The apertures 73 in the supporting sleeve 69 are preferably located to register with the apertures in the spacing members 77.

10 In this embodiment the wing nut 70 has been removed and there has been substituted a silencer, which comprises a spring pressed one-way check valve, indicated in its entirety by the numeral 212. This check valve permits the flow of liquid in the 15 proper direction through the strainers to the pump, but places a predetermined suction resistance on the line, such as, for example, from five to ten inches of mercury, and it is found that this 20 device effectively silences the singing noise of the pump, which would otherwise go back to the tank and be magnified by the tank acting as a sound box.

This suction on the line is believed to cause the 25 gasification of the volatile elements of the liquid fuel, and these volatile elements or gases effect a cushion action between the teeth of the gears of the pump which prevents the singing noise, which would otherwise be present.

Another possible way of eliminating this singing 30 noise is to bleed air into the suction side of the pump to cause a cushion action on the teeth, but this is considered bad practice from the point of view of reduction of the volume of the pump and permitting air to get into the fuel line.

35 Another theory advanced by certain engineers regarding the silencing action is that due to the restriction at the silencer there is a marked change in the velocity of the oil at the point where it passes through the restriction and that this abrupt change in velocity breaks up any vibrations 40 which may be traveling back through the oil, and thereby prevents the sound from reaching the tank.

The silencer 212 may consist of an internally 45 threaded outer sleeve 213, the threads of which engage the end of the strainer sleeve 68. At its upper end this silencer sleeve 213 has an annular shoulder on the inside for receiving the outwardly extending flange 214 carried by a valve sleeve 50 215. The valve sleeve 215 has an inwardly extending flange 216 surrounding an aperture which receives but does not pass the ball valve 217, and the ball valve 217 is pressed by a spring 218, the other end of which is seated upon a plate 219 having an inwardly turned edge 220. The outer 55 end of sleeve 213 is spun over to secure the plate 219 and flange 214 in place, and the sleeve 215 is sufficiently spaced from the internally threaded sleeve 213 so that strainer sleeve 68 may be threaded into the sleeve 213. Sleeve 213 acts 60 as a nut to secure the strainer sleeve 68 in place on the partition 64.

The wire screen discs thus assume a substantially frusto-conical shape which gives them 65 greater stiffness and increases the effective screen area over that of any other shape of strainer unit. The liquid in the strainer chamber 43 passes in at the inlet port 44 and surrounds the strainer units 74 passing through the screen to the interior of each strainer unit, thence to the 70 apertures 79 and apertures 73 into the tube 69 and out the tube 69 into the upper chamber 85 of the strainer housing.

The wall 57 between the strainer housing 42 75 and pump housing 41 supports a downwardly

and laterally extending metallic formation 82 which is connected to the gear housing 58. This metallic connection is provided with a cored conduit 86 which communicates with the chamber 85 at the port 87 and which extends into the gear 5 housing 58 to a point 88 at the right side of the gears in Fig. 2.

The gear housing 58 is provided with a pair of transversely extending bores 89, 90 forming bearings for the pump shaft 23 and pump shaft 91. 10 At each end of the bores 89 and 90 there is formed the counterbores 92, 93, 94, 95. Counterbores 92, 93 are adapted to receive the relatively narrow high pressure gears 96, 97 of the pump, while counterbores 94, 95 are adapted to receive the 15 low pressure gears 98, 99 which are adapted to pump up an excess supply of liquid fuel from the tank 12 to feed the high pressure gears 96, 97. Counterbores 92 to 95 inclusive closely fit the periphery of the toothed gears 96-99 inclusive, 20 and counterbores 92-95 inclusive are formed with flat end shoulders 100 for engaging the flat end surfaces of the gears.

The depths of the counterbores 92-95 correspond respectively to the thickness of the gears 25 so that the outer ends of the gears flatly engage the corresponding flat surfaces on the end plates 21, 101, and the gears substantially fill their respective chambers with exception, of course, of the spaces between the teeth and the bores in 30 the gears, which bores are filled by the pump shafts 23, 91.

The gear 99 is preferably keyed or otherwise secured to the shaft 23 by means of the removable pins 102, while the pin 103 causes the gear 97 to rotate with shaft 23. Gear 96 may be loosely mounted on shaft 91, being driven by gear 97 and the gear 98 may be loosely mounted on shaft 91, being driven by gear 99. The shaft 91 comprises a short stub shaft having a central cylindrical portion 104 of larger size fitting in the bore 89, and having the reduced end portions 105 fitting in the complementary bores in the gears 96, 98, and the ends of the shaft being plane surfaces at right angles to the axis of the shaft. 45

The shaft 23 may comprise a substantially cylindrical shaft with a flattened end 106 for engagement with driving devices, and likewise having an enlarged portion 107 fitting within the bore 90. The gears 97 and 99 have bores fitting on 50 the reduced portions 108, 109 of shaft 23.

Referring to Figs. 4 and 6, these are sections which show the connection between the inlet conduit 86 from strainer to pump and the gear chambers. Inlet conduit 86 leads to a point 87 55 between the upper and lower low pressure gears 98, 99, and at one end of the gears. In Fig. 4 the low pressure gear 99 is seen from above and the conduit 86 is in communication with the space between the gears at the right hand side and at 60 one end of the gears through a slot 110 extending from end 87 of conduit 86 in a direction parallel to the axes of the shafts 23, 91.

The right hand side of the low pressure gears 98, 99 in Fig. 4 is the suction side, shown by the 65 arrows, and the left hand side of the gears 98, 99 in Fig. 4 is the low pressure output.

Referring now to Fig. 2, it will be observed that the gear housing 58 is also supported at the left hand side of the pump housing 41 by the inwardly extending lug 61, back of which is located a conduit 111 communicating at the left end with the cored reservoir space 124. Conduit 111 also extends toward the right in Fig. 4 to a point between the upper and lower gears 98, 99, but at 75

one side thereof and is in communication with the toothed spaces between gears through the slot 113 which extends in a direction parallel to the axes of the shafts 23, 91 and parallel to the direction of the teeth. The output from the low pressure gears is, therefore, through the slot 113 and conduit 111 into the low pressure chamber 124, 60, 120.

The left hand wall 114 between the pump housing 41 and the pressure regulator valve housing 40 supports a lug 115 which may be substantially rectangular in elevation, as shown in Fig. 2, and is provided with a semi-cylindrical end 116, as shown in Fig. 5.

Surrounding the lug 115 is an annular space 117 which forms a part of the pressure regulator valve chamber 112. Further communication between the pump housing chamber 60 and the pressure regulator valve chamber 112 is provided through the conduits or bores 118, 119 which extend axially of the lug 115, the latter bore 119 communicating with the cored reservoir 120 (Fig. 2). The bores 118, 119 and space 120 constitute a part of the fuel returned from the pressure regulator valve to the pump reservoir 60 and, as previously stated, all of the space inside the pump housing 41, with the exception of the gear housing 58 and its supporting lugs 61, 62, is cored out to provide a reservoir 60.

This reservoir 60 practically completely surrounds the gear housing 58 so far as it is possible to do so, and it constitutes a sound deadening liquid enclosure about the gear pump; that is, the spaces 60 and 120 in Figs. 2 and 3 are part of the oil reservoir above and below the gear pump. The space 121 at the right of the gear housing 58 in Fig. 2 is a further part of the oil reservoir enclosing the gear housing at the right. The cored spaces 122, 123 at the bottom and top of Fig. 6 also constitute portions of the oil reservoir surrounding the gear pump, and the cored space 124 in Fig. 4, which is behind the lug 61, provides communication between the lower part of the reservoir 120 and the upper part 60 past the lug 61. In a similar way at the right hand side of Fig. 2 the cored space 121 provides communication between the lower cored opening 120 and the upper cored opening 60, on the right hand side of the gear pump in Figs. 2 and 4, extending past the lug 62 which encloses pump intake conduit 86.

It will thus be observed that the reservoir 60, 120, 121, 124 completely surrounds the gear pump housing 58 and insulates, so far as possible to do so, the gear pump from the outer casing. This reservoir also constitutes an enlarged space in the fuel line between the first or low pressure stage of the pump and the pressure regulator valve chamber into which the liquid fuel must pass, and it reduces the pulsations in the liquid fuel which are caused by the gear pump. Each tooth of the gears naturally causes a pulsation or pressure wave in the liquid fuel which it impels, but as the liquid fuel passes into this reservoir its velocity is diminished, since the same volume of liquid flows through every cross section of the liquid path. Thus the velocity is diminished in this reservoir and the pulsations are absorbed by the mass of liquid in the reservoir.

The oil surrounding the gear pump also deadens the transmission of sound to the air, and the increased mass of the metal surrounding the gear pump also serves to absorb the sound. It is practically impossible to determine the exact theory upon which the noise or tone due to the gear pump

is eliminated but the improved structure as shown herein accomplishes this result and is a marked improvement over the devices of the prior art.

Referring now to Fig. 4, the supply of liquid fuel which is pumped up into the reservoir 60, 120, 5 121, 124 is conducted to the high pressure gears through a cored conduit 125 which extends into the space between the upper and lower shafts 23, 91 adjacent the left end of the shafts in Fig. 3 and at the lower end of the shafts in Fig. 4. This conduit 125 is in communication with the toothed spaces between the high pressure gears 96, 97 through a slot 126 which extends in a direction parallel to the axes of the shafts and parallel to the teeth. Conduits 125, 126 constitute the 15 high pressure intake for the gears 96, 97.

Another conduit 127 provides communication between the pressure regulator valve chamber 112 and the high pressure output side of the gears 96, 97. Conduit 127, Fig. 4, extends to the right 20 to a point between the upper and lower shafts 23, 91 and communicates with the high pressure output side of gears 96, 97 through the axially extending slot 128. Thus the high pressure stage 25 of the gear pump, comprising gears 96, 97, takes the liquid fuel from the reservoir surrounding the gear pump through the conduits 125, 126, and discharges it through the conduits 128, 127 into the pressure regulator valve chamber 112.

In order to provide access to the interior of 30 the pump reservoir 60, 120, 121 and to provide for the return of surplus liquid fuel to the tank in a two pipe system, the pump housing 41 is provided at its lower side with a threaded outlet bore 129. If a one pipe system is desired, this outlet bore 35 129 may be closed by a threaded plug like the plug 47, in which case the plug 130 in the bore 131 of partition 57 should be removed so as to provide direct communication between the strainer chamber 43 and the reservoir 121. Instead of returning 40 excess liquid fuel to the tank, it is returned from the reservoir 121 under these conditions, with a one pipe system, to the strainer chamber 43, thereby reducing the amount which is sucked up through the suction conduit 14. 45

The preferred form of use of the invention, however, comprises the use of a return pipe 15, and the purpose of the removable plug 130 is merely to adapt this preferred form of fuel supply unit to one pipe systems as well as two pipe systems to meet both types of conditions which might be encountered in old installations.

With a two pipe system, the threaded bore 129 receives a threaded pipe connection 132 which has an upwardly extending tube or pipe 133 projecting into the reservoir 121 to the point 134, which is the end of the pipe. The conduit 15 communicating with standpipe 133 is the return conduit for the excess liquid fuel which is pumped up into the reservoir 121 by the low pressure stage. Since 60 the end 134 of the return pipe extends up into the reservoir, liquid cannot flow back from reservoir 121 until it covers the end of the return pipe, and there will always be a supply of liquid in the reservoir 60, 121 which extends to the point above 65 the intake slot 126 of the high pressure gears.

The present pump is self-priming by virtue of the substantial removal of output resistance from the low pressure output or suction stage of the pump. Since the suction stage merely pumps up 70 liquid which is provided with a free return 15 to the tank from the reservoir 60, 121, as soon as the pump starts the low pressure stage is capable of discharging air back to the tank 12 and thereafter sucking up liquid which is discharged 75

into the reservoir 60, 121. This makes the pump self-priming under practically all conditions, even when all of the liquid is exhausted from the pump, and a supply of liquid fuel is provided for the high pressure stage from the reservoir 60, 121 as soon as the pump starts. The standpipe 133 is a useful auxiliary feature which further aids the immediate supply of liquid to the high pressure stage by retaining in the reservoir 60, 121 a level of liquid up to the end of the standpipe for immediate use.

The liquid fuel is, therefore, supplied under pressure through the conduit 127, to the pressure regulator valve chamber 112, and any excess over that utilized by the oil burner may be discharged back to the reservoir 60, 121 through the conduit 120 which is controlled by valves, hereinafter to be described.

The pressure regulator valve housing 40 is substantially cylindrical in plan and is provided with an outlet or burner port 135 located in a downwardly extending lug 136. This outlet port is threaded to receive the threaded metal plug 137, having a cylindrical counterbore 138 communicating with a port 139. Plug 137 has a non-circular outer portion 140 which is threaded home against the end of the lug 136, with a gasket 141 interposed.

The lower end 142 of plug 137 is threaded to receive the usual nipple 143 which is rotatably mounted on the burner supply conduit 16. Mounted in the counterbore 138 is a shouldered metal sleeve 144, having its lower cylindrical end in close frictional engagement with the interior of bore 138. An outwardly extending shoulder 145 determines the final position of sleeve 144, and sleeve 144 is provided with a bore 146 communicating with bore 139. The upper end of bore 146 may be made frusto-conical to provide a seat for the needle valve 147, which is mounted upon the lower end of the piston 148.

Piston 148 is provided with a peripherally extending groove 149, which is adapted to provide communication between the port 150 and port 151 in the sleeve 166 when the groove 149 is in registry with ports 150, 151. Groove 149 is so located, however, that it is out of registry with the ports 150, 151 when the needle valve 147 is upon its seat so that the needle valve port 146 is opened first and afterwards, on further movement of the piston 148, the ports 150, 151 are placed in communication with each other.

Piston 148 comprises a substantially cylindrical member provided at its lower end with an enlarged aperture 221 for permitting movement of a needle valve 147 therein. The needle valve 147 has a ball 222 located on its inner end, and the ball 222 engages a complementary socket in a plug 223 located inside the bore 224 in the piston. The ball 222 thus permits universal movement of the needle valve in the enlarged bore 222 and thus the needle valve finds its seat irrespective of the position of the piston.

Piston 148 is fixedly mounted with respect to an end plate 153, the edges of which are engaged by the lowermost fold of a bellows 154, forming a closed expansible chamber. The opposite end of bellows 154 is secured upon an annular plate 155, having an aperture of sufficient size to receive the bellows, and projecting laterally into the counterbore 156 in the housing 40.

Counterbore 156 is threaded to receive a threaded cover 157, and the annular plate 155 may be clamped between the end of the plug or the cover plug 157 and the annular shoulder 158.

Cover plug 157 is also provided with a threaded bore 159 for receiving the threaded screw bolt 160, which may be secured in place by lock nut 161. The cover plug is also preferably provided with a threaded lug 162 surrounding the screw bolt 160 for receiving the cap 163. The lower end of screw bolt 160 bears against a spring plate 164 which has a centrally located semi-circular portion and an outwardly extending flange 165, forming a seat for a compression spring 166a. 10

The spring 166a engages the end plate 153 in the bellows 154 and tends to hold the needle valve 147 closed, but the valves may be opened by fluid pressure acting upon the bellows 154 in the housing 40. The tension of the spring 15 166a may be adjusted by means of the screw bolt 160 so that the bellows will be opened at any predetermined pressure desired. The sleeve 166 may comprise a metal member of metal dissimilar from the piston 148. For example, the 20 piston may be made of steel and the sleeve of brass, and the sleeve 166 has a close frictional fit in the bore 152 in lug 115. The ports 150, 151 are adapted to register with the ports 118, 119 in the lug 115. Bore 168 in sleeve 166 may be 25 considered as a part of the by-pass ports 118, 119, 150, 151, in which is located the piston 148 for controlling the by-pass port, and the needle valve 147 is likewise located in the burner outlet port 146. 30

The housing 40 is preferably provided with a threaded outlet port 169, which is closed by the threaded plug 170, which may be utilized for an auxiliary outlet or inlet, if desired, or for observing the action of the valve, without completely disassembling it.

The port 119 communicates with the reservoir space 120, 121 surrounding the pump, and the piston valve 148 is thus adapted to by-pass back to the reservoir such amount of liquid fuel as is 40 not required to feed the burner.

The course of the fuel through the device is as follows: Fuel is drawn in through the suction pipe 14 from the supply 13 in the tank 12, passing into the chamber 43 of strainer housing 42. The 45 liquid fuel passes through the strainers 74 into the tube 69, thence into the chamber 85 and out through conduit 86 (Fig. 4), slots 110, to the intake side of the suction stage of the pump, comprising the gears 98, 99. 50

The liquid fuel is discharged from the gears 98, 99 at slot 113 and passes through conduit 124 into the space 122, 123, 120, 121, 60, surrounding the pump housing 58. From this space it is fed into the high pressure stage of the pump, 55 comprising the gears 96, 97, through the slot 126, and is discharged through slot 128 at the opposite side of the gears into conduit 127. Conduit 127 leads into the chamber 112 of the pressure regulator valve housing 40, and the liquid fuel 60 under pressure acts against the bellows 154 to compress the bellows. When the pressure has reached a sufficient amount to compress the bellows, the needle valve 147 is opened and the pressure continues to rise until it has reached 65 the predetermined amount at which the valve is set for operation of the burner. On further increase in pressure the bellows 154 is compressed sufficiently to cause the piston valve 148 to open the ports 150, 151 and any excess of oil is by- 70 passed back through ports 118, 119, 150, 151 to the reservoir 60, 120, 121, 123 surrounding the pump.

The standpipe 133 projects up into the liquid fuel in the reservoir and prevents flowing back 75

- of fuel except when it rises above the end 134 of the standpipe, but any excess of fuel above this level is permitted to flow back freely through pipe 133 and pipe 15 to the tank 12. If it is desired to use this unit with a one pipe arrangement, then the port 129 may be plugged up and the plug 130 removed so that any excess oil may be discharged back from the suction stage into the strainer chamber 43.
- 10 The present unit is thus equally adapted for two pipe systems or one pipe systems, and may be used with or without a free return to the tank.

15 It is found that the pump noise present in ordinary gear pumps is eliminated by means of the present arrangement and the pulsations or vibration in the liquid fuel are not carried back through the pipe to the tank. The interposition of the reservoir in between the low pressure stage 20 and the high pressure stage causes the flow of oil to slow up or lose its velocity and breaks up the vibration. The oil surrounding the pump also deadens the transmission of sound to the air and the increased mass of metal and oil act as 25 sound absorbers, making the present pumping arrangement substantially noiseless for all practical purposes.

30 While we have illustrated a preferred embodiment of our invention, many modifications may be made without departing from the spirit of the invention, and we do not wish to be limited to the precise details of construction set forth, but desire to avail ourselves of all changes within the scope of the appended claims.

35 Having thus described our invention, what we claim is new and desire to secure by Letters Patent of the United States, is:

1. In a fuel supply unit for oil burners or the like, a casing having two laterally spaced cylindrical portions with the axes of said cylindrical portions extending parallel to each other, said cylindrical portions being joined by an integral medial housing portion of partially cylindrical form having its axis extending at substantially 40 right angles to the axes of the first-mentioned cylindrical portions, one of said cylindrical portions forming a strainer housing, and the other of said cylindrical portions forming a regulator valve housing, a web disposed between said 45 strainer housing and said medial portion, and a second web disposed between said regulator valve housing and said medial portion, an integral inwardly projecting lug formed in said medial housing, said lug supporting a pump casing substantially surrounded by a space communicating 50 with said strainer housing and adapted to be substantially filled with fuel oil to absorb the pump noise, and said lug having a discharge aperture extending from the interior of said 55 pump housing to said regulator valve housing, end plates on said medial housing portion for closing the same, and cover means for each of said cylindrical portions, said strainer housing having a transversely extending partition, a 60 downwardly extending perforated tubular member and a plurality of wire mesh wafers carried by said tubular member.

65 2. In a fuel supply unit for oil burners or the like, a casing having two laterally spaced cylindrical portions with the axes of said cylindrical portions extending parallel to each other, said cylindrical portions being joined by an integral medial housing portion of partially cylindrical form, having its axis extending at substantially 70 right angles to the axes of the first-mentioned

cylindrical portions, one of said cylindrical portions forming a strainer housing, and the other of said cylindrical portions forming a regulator valve housing, a web disposed between said strainer housing and said medial portion, a second web disposed between said regulator valve housing and said medial portion, an integral inwardly projecting lug formed in said medial housing, said lug supporting a pump casing substantially surrounded by a space communicating 10 with said strainer housing and adapted to be substantially filled with fuel oil to absorb the pump noise, said lug having a discharge aperture extending from the interior of said pump housing to said regulator valve housing, plates on said 15 medial housing portion for closing the same, cover means for each of said cylindrical portions, said regulator valve housing having an inwardly projecting lug provided with a conduit communicating with the space in said medial housing portion 20 surrounding said pump housing, a piston valve slidably mounted in a bore transversely to said conduit, said piston valve having a circumferentially extending slot providing communication between parts of said conduit when in predetermined position, a conical valve member universally mounted on the end of said piston valve for controlling an outlet port to a burner, and a pressure responsive bellows for controlling both 25 of said valves.

30 3. In a fuel supply unit for oil burners or the like, a casing having two laterally spaced cylindrical portions with the axes of said cylindrical portions extending parallel to each other, said cylindrical portions being joined by an integral 35 medial housing portion of partially cylindrical form, having its axis extending at substantially right angles to the axes of the first-mentioned cylindrical portions, one of said cylindrical portions forming a strainer housing, and the other 40 of said cylindrical portions forming a regulator valve housing, a web disposed between said strainer housing and said medial portion, a second web disposed between said regulator valve housing and said medial portion, an integral inwardly projecting lug formed in said medial housing, said lug supporting a pump casing substantially surrounded by a space communicating with said strainer housing and adapted to be substantially filled with fuel oil to absorb the 45 pump noise, said lug having a discharge aperture extending from the interior of said pump housing to said regulator valve housing, and plates on said medial housing portion for closing the same, cover means for each of said cylindrical 50 portions, one of the cover plates for said medial housing having a laterally projecting seal housing, a pump shaft projecting out of said seal housing, a cover plate for said seal housing, a diaphragm having its outer edge clamped between said cover plate and seal housing and having a metallic fitting surrounding said shaft and provided with a flat end surface, a collar having a complementary surface and having a fluid-tight connection with said shaft, said collar 55 having a sliding contact with said fitting for preventing leakage along said shaft.

60 4. In a fuel supply unit for oil burners or the like, a pump comprising an inner housing having bores for receiving pumping gears, low pressure 70 stage gears and high pressure stage gears in said inner housing, an outer housing comprising a metal shell in spaced relation to said inner housing, said outer shell being joined to and supporting said inner housing by a pair of joining 75

lugs, and said lugs having intake and outlet conduits formed therein communicating with the low pressure stage inlet and the high pressure stage outlet respectively, and conduits providing communication from said low pressure stage output to the space between said housings and from said space to the intake of said high pressure stage.

5. In a fuel supply unit for oil burners or the like, a pump comprising an inner housing having bores for receiving pumping gears, low pressure stage gears and high pressure stage gears in said inner housing, an outer housing comprising a metal shell in spaced relation to said inner housing, said outer shell being joined to and supporting said inner housing by a pair of joining lugs, and said lugs having intake and outlet conduits formed therein communicating with the low pressure stage inlet and the high pressure stage outlet respectively, and conduits providing communication from said low pressure stage output to the space between said housings and from said space to the intake of said high pressure stage, and an upwardly projecting conduit located in said space and providing a free return conduit from said space to a supply tank.

6. In a liquid fuel supply unit for oil burners, the combination of a housing provided with a pump chamber, a valve chamber and a strainer chamber, said strainer chamber having an inlet port adapted to be connected to a source of liquid fuel supply and having an outlet port communicating through said housing with the pump chamber inlet port, a strainer unit in said strainer chamber and interposed between the strainer inlet and outlet ports, said pump chamber having an outlet port communicating with said valve chamber, pressure responsive means in said valve chamber and subject to the pressure of liquid fuel supplied from said pump outlet port, said valve chamber having a burner outlet port and a by-pass outlet port, valve means actuated by said pressure responsive means for controlling said burner outlet port and said by-pass outlet port whereby the by-pass outlet port is adapted to discharge from the valve chamber any excess of liquid fuel above that passed by the burner outlet port, conduit means within the housing leading from the by-pass outlet port and having communication respectively with the inlet port of the pump and with a pipe leading to the source of fuel supply, and closure means for selectively closing one or the other of said communications whereby said fuel supply unit may be used in a one pipe or two pipe supply system.

7. In a liquid fuel supply unit for oil burners, the combination of a housing provided with a pump chamber, a valve chamber and a strainer chamber, said strainer chamber having an inlet port adapted to be connected to a source of liquid fuel supply and having an outlet port communicating through said housing with the pump chamber inlet port, a strainer unit in said strainer chamber and interposed between the strainer inlet and outlet ports, said pump chamber having an outlet port communicating with said valve chamber, pressure responsive means in said valve chamber and subject to the pressure of liquid fuel supplied from said pump outlet port, said valve chamber having a burner outlet port and a by-pass outlet port, valve means actuated by said pressure responsive means for controlling said burner outlet port and said by-pass outlet port whereby the by-pass outlet port is adapted to discharge from the valve chamber any excess of liquid fuel supplied to said valve chamber from the pump chamber in excess of the liquid fuel passed by the burner outlet port, said unit having selective conduit means within said unit leading from the by-pass outlet port and having communication respectively with the inlet port of the pump chamber and with an outlet adapted to be connected to the source of fuel supply, and closure means for selectively closing one or the other of said communications where-

cess of liquid fuel above that passed by the burner outlet port, conduit means within the housing leading from the by-pass outlet port and having communication respectively with the inlet port of the pump and with a pipe leading to the source of fuel supply, and closure means for selectively closing one or other of said communications whereby said fuel supply unit may be used in a one pipe or two pipe supply system, one of said closure means comprising a threaded plug provided with a tool receiving formation and located in a threaded bore inside said housing in substantial alignment with an external port whereby a screw driver or other tool may be inserted through said latter port to remove said threaded plug.

8. In a liquid fuel supply unit for oil burners, the combination of a housing provided with a pump chamber, a valve chamber and a strainer chamber, said strainer chamber having an inlet port adapted to be connected to a source of liquid fuel supply and having an outlet port communicating through said housing with the pump chamber inlet port, a strainer unit in said strainer chamber and interposed between the strainer inlet and outlet ports, said pump chamber having an outlet port communicating with said valve chamber, pressure responsive means in said valve chamber and subject to the pressure of liquid fuel supplied from said pump outlet port, said valve chamber having a burner outlet port and a by-pass outlet port, valve means actuated by said pressure responsive means for controlling said by-pass outlet port whereby the by-pass outlet port is adapted to discharge from the valve chamber any excess of liquid fuel above that passed by the burner outlet port, conduit means within the housing leading from the by-pass outlet port and having communication respectively with the inlet port of the pump and with a pipe leading to the source of fuel supply, and closure means for selectively closing one or the other of said communications whereby said fuel supply unit may be used in a one pipe or two pipe supply system.

9. In a liquid fuel supply unit for oil burners, the combination of a housing provided with a pump chamber and a valve chamber, with pumping means in said pump chamber adapted to pump a volume of liquid fuel in excess of that required for the burner, said housing having an inlet port communicating with the inlet side of the pump chamber and adapted to be connected to a source of liquid fuel supply, and said housing having a pump chamber outlet port communicating with said valve chamber, pressure responsive means in said valve chamber and subject to the pressure of liquid fuel supplied from said pump outlet port, said valve chamber having a burner outlet port and a by-pass outlet port, valve means actuated by said pressure-responsive means for controlling said by-pass outlet port, whereby the by-pass outlet port is adapted to discharge from the valve chamber the excess of liquid fuel supplied to said valve chamber from the pump chamber in excess of the liquid fuel passed by the burner outlet port, said unit having selective conduit means within said unit leading from the by-pass outlet port and having communication respectively with the inlet port of the pump chamber and with an outlet adapted to be connected to the source of fuel supply, and closure means for selectively closing one or the other of said communications where-

by said fuel supply unit may be arranged to return excess liquid fuel to the intake port of the pump or to the source of fuel supply.

10. In a liquid fuel supply unit for oil burners, the combination of a housing provided with a pump chamber and a valve chamber, with pumping means in said pump chamber adapted to pump a volume of liquid fuel in excess of that required for the burner, said housing having an inlet port communicating with the inlet side of the pump chamber and adapted to be connected to a source of liquid fuel supply, and said housing having a pump chamber outlet port communicating with said valve chamber, pressure responsive means in said valve chamber and subject to the pressure of liquid fuel supplied from said pump outlet port, said valve chamber having a burner outlet port and a by-pass outlet port, valve means actuated by said pressure-responsive means for controlling said by-pass outlet port, whereby the by-pass outlet port is adapted to discharge from the valve

chamber the excess of liquid fuel supplied to said valve chamber from the pump chamber in excess of the liquid fuel passed to the burner outlet port, said unit having selective conduit means within said unit leading from the by-pass outlet port and having communication respectively with the inlet port of the pump chamber and with an outlet adapted to be connected to the source of fuel supply, and closure means for selectively closing one or the other of said communications whereby said fuel supply unit may be arranged to return excess liquid fuel to the intake port of the pump or to the source of fuel supply, one of said closure means comprising a threaded plug provided with a tool receiving formation and located in a threaded bore inside said housing in substantial alignment with an external port whereby a tool may be inserted through said latter port to remove or install said threaded plug. 5 10 15 20
